UNITED STATES PATENT OFFICE.

JOSEPH M. SALADINER, OF BRYAN, TEXAS.

POISON DISTRIBUTING ATTACHMENT FOR BOLL-WEEVIL EXTERMINATORS.

Application filed April 20, 1922. Serial No. 555,704.

To all whom it may concern:

Be it known that I, JOSEPH M. SALADINER, a citizen of the United States, residing at Bryan, in the county of Brazos and State of Texas, have invented a new and useful Poison Distributing Attachment for Boll-Weevil Exterminators, of which the following is a specification.

This invention relates to apparatus for 10 distributing poisons and is designed primarily for use in connection with boll weevil exterminators such as disclosed, for example, in Patent No. 1,354,215 issued to me on Sept. 28, 1920.

15 In machines of the type mentioned there are provided hoods supported by portable structures and adapted to spread over rows of plants being treated. Poison, in the form of a dust or the like, is distributed under 20 the hood so as to be applied to the plants.

It is an object of the invention to provide 25 poison distributing nozzles adjustably mounted in a novel manner within the top of the hood, it being possible to shift the nozzles to any desired positions relative 30 to each other after which they can be suitably secured against accidental displacement.

With the foregoing and other objects in 35 view which will appear as the description proceeds, the invention resides in the combination and arrangement of parts and in the details of construction hereinafter described and claimed, it being understood that, within 40 the scope of what is claimed, changes in the precise embodiment of the invention shown can be made without departing from the spirit of the invention.

In the accompanying drawings the preferred form of the invention has been shown.

In said drawings

Figure 1 is a plan view of a hood having the present improvements combined therewith.

45 Figure 2 is an enlarged section on line 2-2, Figure 1.

Figure 3 is a plan view of the attaching ring of the nozzle.

Referring to the figures by characters of 50 reference 1 designates the frame of a hood, the same having a covering 2 of a suitable heavy fabric while a screen 3 can be provided along the bottom of the hood. It is to be understood that this hood can be of 55 any construction desired and, in itself, constitutes no part of the present invention.

Formed within the fabric top of the hood are circular openings 4 and arranged on the hood so as to extend around the openings are attaching rings 5 each having an annular 60 series of openings 6 whereby the ring can be attached to the hood by stitching as shown at 7.

The ring 5 has an annular upwardly and inwardly turned flange 8 along the inner 65 edge thereof and a portion of this flange merges into a tongue 9 which extends to the center of the ring where it is provided with a central opening 10 and an annular series of depressions 11. 70

A disk 12 is mounted on the ring 5 and has its peripheral portion downturned as shown at 13 so as to lap and frictionally engage the flange 8. A centering and binding screw 14 extends through the center of the 75 disk and engages the wall of the opening 10. Thus by loosening the screw the disk can be rotated but by tightening the screw a series of small projections 15 on the disk will be forced into the recesses 11 and the 80 disk thus held against rotation.

Formed within the disk 12 near its periphery is an opening 16 and secured to the disk so as to extend across the opening is a flared nozzle 17 having an upwardly extending tubular portion 18 to which is clamped or otherwise secured one end of a flexible 85 hose 19.

It will be apparent that by rotating the disk 12 the nozzles 17 can be adjusted toward or from each other and also relative to the edges of the hood, thus to bring the nozzles in proper positions to discharge poison at the most advantageous points. This arrangement is particularly desirable 95 where adjustment of the nozzles should be made in order to adapt the machine for use on rows at different distances apart.

What is claimed is:—

1. The combination with a hood having 100 openings therein, of a disk extending over and rotatable relative to each opening, a nozzle carried by each disk, means for conducting material to the nozzles, and means for holding each disk against rotation. 105

2. The combination with a hood having an opening therein, of a disk rotatably mounted above and extending over the opening, a nozzle fixedly connected to the disk, means for conducting material to the nozzle, 110 and means for holding the disk against rotation.

3. The combination with a hood, of an attaching ring secured to the hood and extending around an opening therein, a disk mounted for rotation on the ring, cooperating means upon the disk and ring for holding the disk against rotation, and a nozzle opening through and movable with the disk.
4. The combination with a hood having an opening therein, of an attaching ring extending around the opening and secured to the hood, a tongue extending inwardly from the ring, a disk mounted for rotation on the ring, means extending through the

centers of the disk and ring for binding them together, cooperating means upon the tongue and disk for holding the disk against rotation, and a nozzle discharging through and movable with the disk.

In testimony that I claim the foregoing as my own, I have hereto affixed my signature in the presence of two witnesses.

JOSEPH M. SALADINER.
